CLAIM

The ornamental design for a front face of a vehicle wheel, as shown and described.

DESCRIPTION

FIG. 1 is a frontal view of the front face of a vehicle wheel according to our novel design;

FIG. 2 is a perspective side view of the front face of a vehicle wheel according to our novel design; and,

FIG. 3 is a sectional view taken along line 3—3 in FIG. 1. The broken line showing of environment in FIG. 3 is for illustrative purposes only and forms no part of the claimed design.
